(57) **CLAIM**

The ornamental design for an interior panel and seat for a vehicle, as shown and described.

DESCRIPTION

FIG. 1 is a front elevational view of an interior panel and seat for a vehicle showing my new design, shown with the seat in the open position;

FIG. 2 is a side elevational view thereof shown with the seat in the closed position;

FIG. 3 is a top plan view thereof, shown with the seat in the open position as in FIG. 1;

FIG. 4 is a front elevational view thereof shown with the seat in the closed position as in FIG. 2; and,

FIG. 5 is a side elevational view thereof shown with the seat in the open position as in FIG. 1.

The broken line showings within the broken lines boundary are for illustrative purposes only and do not form part of the claimed design.
